[57] CLAIM

The ornamental design for a front panel for a computer, as shown and described.

DESCRIPTION

FIG. 1 is a top, front, left side perspective view of a front panel for a computer showing my new design;
FIG. 2 is a top plan view thereof on an enlarged scale;
FIG. 3 is a bottom plan view thereof on an enlarged scale;

FIG. 4 is a left side elevational view thereof on an enlarged scale;

FIG. 5 is a right side elevational view thereof on an enlarged scale;

FIG. 6 is a front elevational view thereof on an enlarged scale;

FIG. 7 is a rear elevational view thereof on an enlarged scale.
